United States Patent Office

Des. 205,352
Patented July 26, 1966

205,352

FARM TRACTOR

Vernon John Lundell, Box 171, Cherokee, Iowa

Filed Nov. 5, 1965, Ser. No. 88,015

Term of patent 14 years

(Cl. D14—3)

FIG. 3FIG. 4FIG. 5FIG. 1 is a side perspective view of a farm tractor showing my new design;

FIG. 2 is a front elevational view of the farm tractor;
FIG. 3 is a top plan view of the farm tractor;

FIG. 4 is a perspective view of the farm tractor as seen from the side thereof opposite the side shown in FIG. 1; and

FIG. 5 is a rear elevational view of the farm tractor.

I claim:

The ornamental design for a farm tractor, substantially as shown.
